INVENTOR

Joseph L. Firm.

UNITED STATES PATENT OFFICE.

JOSEPH L. FIRM, OF JERSEY CITY, NEW JERSEY.

REEL AND ROD FOR WINDING PAPER AND PROTECTING THE SAME IN THE ROLL.

SPECIFICATION forming part of Letters Patent No. 297,775, dated April 29, 1884.

Application filed February 10, 1883. (Model.)

To all whom it may concern:

Be it known that I, JOSEPH L. FIRM, of Jersey City, in the county of Hudson and State of New Jersey, have invented certain new and useful Improvements in Reels and Rods for Winding Paper and Protecting the Same in the Roll, of which the following is a full, clear, and exact description.

The object of the invention is to roll paper at the mill for the printing-press or paper-damping machine, so as to dispense with a tube or tubular core on which the paper has heretofore been wound, and to make the rod heretofore employed for binding on the protecting-heads subserve both purposes, thus also saving the cost of returning the tubes.

The invention consists in the details of construction, as hereinafter specifically set forth and claimed.

In the accompanying drawings, in the several figures of which like parts are similarly designated, Figure 1 is a side elevation of sufficient of the discharge end of a paper-making machine to illustrate one part of my invention. Fig. 2 is a partly-sectional elevation of my improved rod, on a larger scale, with a cap or reel socket in position, and a friction-wheel for use in damping-machines, also in position. Fig. 3 is a perspective view of a cap or reel socket for the rod. Fig. 4 is a cross-section of one of the roll - protecting heads; and Fig. 5 is a partly-sectional view, in elevation, of a roll of paper made in accordance with my invention.

A is the rotary discharge-roller of a paper-making machine set in bearings in the frame B, and suitably driven in the direction indicated by the arrow, and at a speed commensurate with the speed of the machine.

C is a rod, the same as or similar to that heretofore used in securing the heads or caps to tube-wound rolls of paper. (See my Re-issued Letters Patent No. 6,533, dated July 6, 1875.) This rod has screw-threaded ends 2 1/2', with which are engaged threaded socket-caps 3 3/4', having squared ends 4 4'. These caps are applied to the rod when it is to receive the web of paper, and they then form journals for it in the boxes G of the automatically-compensating winding-frame D; their squared ends 4 or 4' serving to receive a removable crank-handle for operating the rod

when desired, and also to permit the use of a wrench in applying and removing them. One of the sockets—say 3', both being not necessarily otherwise than exactly alike—may receive the wheel 5, which is a friction-wheel operable in a paper-damping machine to regulate the paying out of the paper from the roll, or in a printing-press to hold back the frame.

E indicates the web of paper being wound. The frame D is hinged to the machine-frame or elsewhere at its lower end, as at F, and is provided with a counter-balance, H, so as to automatically adjust itself to the increasing size of the winding-roll, at the same time exerting a tension on the paper sufficient to prevent its crumpling, creasing, or its winding irregularly.

The heads 8 employed in connection with these rolls of paper made on rods are preferably discous boards provided with central orifices having metallic screw-threaded bushings 9, which are engaged with the threaded ends 2 1/2' of the rod C, when said heads are applied to a roll of paper, and said heads may be retained upon said rod by thumb-nuts 13 or other equivalent fastenings. In Fig. 5 the parts are all shown in position, and from this figure the operation of my invention will be perfectly apparent. The heads 8 may be applied to the rod before the paper is wound on the same, if desired.

What I claim is—

1. A paper-roll head-holding rod provided with threaded ends, and socketed caps adapted to be applied thereto to admit of the rotation of the rod to roll paper thereon, substantially as shown and described.

2. A mill-wound roll of paper having a central rod, directly upon which the paper is wound, and heads attached to and secured by said rod, substantially as shown, and described.

3. The combination of the rod, the winding-frame and its counter-balance, means to feed the paper to said rod, and means to operate said rod, substantially as described.

JOSEPH L. FIRM. [L. S.]
